United States Patent Office

Des. 191,371
Patented Sept. 19, 1961

191,371

CIGARETTE LIGHTER OR SIMILAR ARTICLE

Alfred Racek, Zwergasse 59, Vienna XVII, Austria, and Johann Raganitsch, Haas Richtergasse 1a, Vienna
XIX, Austria

Filed Mar. 29, 1960, Ser. No. 59,925

Claims priority, application Austria Oct. 10, 1959

Term of patent 14 years

(Cl. D48—27)

Fig. 1

Fig. 2

Fig. 3

FIG. 1 is a perspective view of a cigarette lighter or similar article, showing our new design;

FIG. 2 is a perspective view thereof as shown in operational position;

FIG. 3 is an exploded view thereof.

The side of the lighter not shown is a mirror image of the side shown and the top and rear thereof are substantially flat and plain.

We claim:

The ornamental design for a cigarette lighter or similar article, as shown and described.
